HOSE NOZZLE

John H. Thompson, Glendale, Calif., assignor to
Arnold Rockvam, Glendale, Calif.

Application October 29, 1946, Serial No. 134,365

Term of patent 7 years

(Cl. D91—1)

To all whom it may concern:

Be it known that I, John H. Thompson, a citizen of the United States and a resident of Glendale, Los Angeles County, California, have invented a new, original, and ornamental Design for a Hose Nozzle, of which the following is a specification, reference being had to the accompanying drawing, forming part thereof.

Referring to the drawing:

Figure 1 is a perspective view of a hose nozzle, showing my new design;

Figure 2 is a view of the discharge end of the nozzle in one operative position;

Figure 3 is a similar view of the discharge end of the nozzle in another position of operation; and

Figure 4 is a view taken from the rear end of the nozzle.

I claim:

The ornamental design for a hose nozzle, as shown.

JOHN H. THOMPSON.
